UNITED STATES PATENT OFFICE.

MICHAEL MURPHY, OF PUEBLO, COLORADO, ASSIGNOR OF ONE-HALF TO
FRED W. LUCCO, OF PUEBLO, COLORADO.

SMELTING-FURNACE.

SPECIFICATION forming part of Letters Patent No. 783,535, dated February 28, 1905.

Application filed May 9, 1903. Serial No. 156,397.

To all whom it may concern:

Be it known that I, MICHAEL MURPHY, a citizen of the United States of America, residing at Pueblo, in the county of Pueblo and State of Colorado, have invented certain new and useful Improvements in Smelting-Furnaces, of which the following is a full, clear, and exact specification.

The accompanying drawings fully illustrate a furnace embodying my invention, and in the said drawings—

Figure 1 is a horizontal section showing a body of molten metal in place. Fig. 2 is a vertical longitudinal section taken on the line *c d* of Fig. 1, the plane of the section on which Fig. 1 is taken being indicated by the line *a b* on Fig. 2. Fig. 3 is a transverse vertical section. Fig. 4 is a detail plan of a portion of the ore-bed or hearth. Fig. 5 is a side elevation of the furnace. Fig. 6 is an end elevation of the furnace.

The walls and body of the furnace are built of brick or similar material and at the front end is a grate *l*, on which the fuel is supported and heat generated. In rear of the grate is a bridge-wall *k*, over which the heat passes to the body of ore, and this bridge-wall is pro-

vided with an internal water-space *j*. Extending from the front face of the bridge-wall to the rear end of the furnace is a bed-plate *n*, and below this bed-plate are longitudinal air-passages *m*, communicating at their front ends with a transverse air-passage *m*², whereby free circulation of air through the bottom of

the furnace is permitted. In order that the air may have access to the greatest possible extent of the surface of the bed-plate, the central portion of the same is supported on T-rails instead of resting directly on the brick

foundation or body of the furnace, as clearly shown in Fig. 3. These rails form part of the system of stay-bars presently referred to. The transverse passage *m*², it will be noticed, is just in rear of the bridge-wall, so that the cold air will be drawn in at the hottest point of the furnace and slightly heated before passing back below the bed-plate. I thus guard against precipitate chilling of the bottom of the melting-chamber and at the same time

maintain an even temperature below the same, so that while the metal will be effectually and quickly melted the cracking or crumbling of the foundation is avoided. Above the bed-plate and in rear of the bridge-wall is a concave elliptical ore-bed or hearth *i*, on which the ore to be treated is fed through a charge-hole *p* in the top of the furnace and a charge-hole *q* in the side wall. The tap-hole *h* is located in the opposite side of the furnace to the charge-hole *q* and below the same, while the skimming-hole *r* is located in the rear end of the furnace and above the tap-hole. In the front end of the side walls of the furnace are located ports *s*, through which hot-air blasts may be forced to drive the floating slag to the skimming-hole. The floor of the hearth or ore-bed is laid in such a manner as to equalize the strain in every direction. As shown clearly in Fig. 4, a single row of bricks is laid along each axis of the elliptical ore-bed, the bricks of which do not break joint at the point of intersection of the rows. The quarter-sections of the ellipse are then filled with bricks which break joint in the usual manner and are arranged in rows that are at right angles to each other.

The floor, as shown clearly in Fig. 3, extends into the side walls of the furnace, the result of this construction and the described peculiar arrangement of the bricks being to permit expansion and contraction to some degree without in any way affecting the strength of the structure.

In order to maintain the unbroken solidity of the mass constituting the walls and body of the furnace and at the same time provide for the expansion due to the intense heat necessary for the successful operation of the furnace, I employ a plurality of longitudinal stay rods or bars *t* and vertical stay rods or bars *w*, placed against the side and end walls of the furnace, and stay-bars *A*, extending through the same below the bed-plate *n*. These several bars are held in place by rods *v* and *x* and a truss-rod *y*, which are provided with eyes or loops on their ends engaging over the stay bars and rods and with turnbuckles *z* at intermediate points of their length. As the

heat varies and the furnace-walls tend to expand or contract, the turnbuckles are manipulated to adjust the rods to the strain, so as to maintain the walls of the furnace intact. Cotter-pins B, inserted through the stay-bars beyond and adjacent to the eyes or loops, prevent the connecting turnbuckle-rods slipping off the ends of the said stay-bars.

In the operation of the furnace the ore is fed onto the hearth and melted, the slag skimmed therefrom, and a charge of molten metal withdrawn through the tap-hole. Inasmuch as the tap-hole is above the bottom of the hearth, there will always be a quantity of molten metal left on the hearth, so that the hearth will be protected against great changes in temperature. Furthermore, this surplus or remaining body of molten metal materially assists in the melting of the fresh charge of ore. The melting-chamber, of which the hearth forms the bottom, being elliptical in shape, there are no cold corners therein; but an even temperature will prevail throughout the same.

The melting-chamber is not only elliptical in plan, but its bottom is concave both longitudinally and transversely, as shown in Figs. 2 and 3, being a true inverted arch without any flat surface. As a result of this construction the edges of the mass of metal are not as deep as the central portion and the heat is more economically employed. By employing an arched roof and an inverted-arch-shaped bottom to the melting-chamber in connection with the system of stay bars or braces and connecting-rods the furnace becomes practically one solid piece of masonry, yet capable of expansion and contraction without injuring any part and especially without cracking or disintegrating the ore-bed, which is subjected to the hardest usage. The

peculiar arrangement of the bricks in the ore-bed, as shown in Fig. 4, plays no small part in this expansion and contraction.

Having thus described my invention, what I claim, and desire to secure by Letters Patent, is—

1. A smelting-furnace having a transverse air-passage below the ore-bed and just in rear of the bridge-wall the ends of which extend through the side walls of the furnace and communicate with the outer air, and a series of longitudinal air-passages beneath the ore-bed communicating at their front ends with the transverse air-passage and having their rear ends communicating with the outer air.

2. A smelting-furnace having an elliptical melting-chamber, the bottom of which is an inverted elliptical arch having a single row of bricks along each axis which do not break joint at the point of intersection of the rows, and having its quarter-sections filled in with bricks arranged in rows at right angles to each other, all the rows in the quarter-sections and along the axes extending into the side walls of the furnace.

3. In a smelting-furnace, the combination with the body thereof having an elliptical melting-chamber, the roof of which is arched and the ore-bed of which is an inverted arch having its ends extended into the side walls of the body of the furnace, stay-bars extending longitudinally through the body of the furnace below the ore-bed and supporting the same, other stay-bars arranged against the outer sides of all the walls of the furnace, and extensible connecting-rods securing the stay-bars.

MIKE. MURPHY.
